UNITED STATES PATENT OFFICE

2,582,805

NEBULIZER OR THE LIKE

George P. Trumbour and Forbes MacGregor,
Needham, Mass., assignors to MacGregor In-
strument Company, Needham, Mass., a corpo-
ration of Massachusetts

Application September 11, 1947, Serial No. 773,330

2 Claims. (Cl. 299—88.5)

1

Our present invention relates to nebulizers or like devices for use in atomizing various liquids.

Certain uses of various liquids require that they be atomized. For example, atomized lacquers are used in hair dressing while, on the other hand, it is frequently desired to use a nebulizer to dispense perfumes or medications which may be costly or which may be intended for use only in small volume.

In accordance with our invention, we provide a nebulizer consisting of a hollow, open-ended body having a supporting base. Within the body is an atomizing unit disposed to discharge atomized liquid through a port with which the upper part or head of the body is formed. The open end of the body is preferably closed by a rotatable cap having a port closing skirt which is provided with one and preferably at least two apertures of different size. Each aperture is registerable with the outlet port so that the cap may be turned into one position in which the nebulizer is sealed, into another position where the larger aperture is in registry with the outlet port, as when a lacquer is to be dispensed, and into a third position where the smaller aperture registers with the outlet port as when a perfume or medication is to be atomized.

While any suitable atomizing means may be employed in our nebulizers, we prefer to use a suction tube that is removably supported in the body by centering means and an air delivery tube seated in the wall of the head portion of the body with its delivery end operatively positioned relative to the suction tube to enable liquid to be withdrawn therethrough and discharged, in atomized form, through the outlet port. The delivery end of the air tube prevents the suction tube from being removed from the body until the air tube is unseated and to ensure the desired relationship between the tubes, the air delivery tube preferably has a seated engagement with the suction tube thereby to cooperate in its support. In addition to the simplicity of construction which such an atomizing unit represents, it also has the advantage that it enables nebulizers to be readily assembled or taken apart as when they are to be thoroughly cleansed.

We prefer that the base and the body be separate and that they and the cap be molded from plastic of the same or different colors. When the

parts are to be molded, the base may be hollow and of frusto-conic section. Interiorly of its rim, the base may have a downwardly and inwardly tapered seat. With such a base, the lower portion of the body is downwardly and inwardly tapered so that a substantial part of it is entrant of the base when seated therein, with said lower portion constituting a well for the liquid to be atomized.

10 The body may advantageously be formed with a skirt, spaced therefrom to establish a recess for the rim of the base and outwardly and downwardly tapered to engage the outer surface of the base in the zone of its seat when the body and the base are united. The cap has a recess to receive the rim of the body and the inner wall of the recess is extended to provide the apertured, port blocking skirt.

15 In the accompanying drawings, we have shown 20 illustrative embodiments of our invention from which these and other of its novel features and advantages will be readily apparent.

In the drawings:

25 Fig. 1 is a vertical section through a nebulizer in accordance with our invention.

Fig. 2 is a section along the lines 2—2 of Fig. 1, and

Fig. 3 is a view similar to Fig. 1 but showing a modification of our invention.

30 The embodiments of our invention shown in the drawings are adapted to be molded from any suitable plastic and each comprises a hollow base 5 of frusto-conic section, a hollow open-ended body, generally indicated at 6, a cap 7 to rotatably seat on the rim 8 of the body 6, and an atomizing unit consisting of an air delivery tube 9 and a suction tube 10.

35 The base 5 has a downwardly and inwardly tapering seat 11 interiorly of its rim 12. The interior of the body 6 preferably tapers uniformly 40 downwardly and inwardly from its rim 8 substantially to its bottom, where it is tapered as at 13 to establish a relatively shallow liquid collecting pocket centrally of which we provide the body 6 with an upstanding and slotted centering ring 14. The hollow body 6 includes an upper or head portion 15 and a lower portion 16 which is exteriorly tapered so that a substantial part of it is 45 entrant of the base 5 when it is in engagement with the seat 11. When the body 6 is thus sup-

ported, its lower portion 16 constitutes a well for the liquid to be atomized and its shallow liquid collecting pocket enables small quantities of relatively expensive medications or perfumes to be atomized.

Preferably, the outer surface of the head portion 15 tapers slightly outwardly and downwardly from its rim 8 and the body 6 has a skirt 17 spaced from the upper part of the well 16 to establish a recess to receive the rim 12 and outwardly and downwardly flared to engage the outer surface of the base 5 in the zone of the seat 11 when the body and the base are united. The head portion 15 has a strengthening rib 18 extending upwardly from the skirt 17 through which extends a port, preferably slightly tapered so that the air delivery tube 9 may be tightly seated therein with its delivery end disposed in alignment with the outlet port 19.

The air delivery tube 9 is adapted to be connected to any conventional bulb, not shown, and has a passage 20 therethrough of reduced diameter adjacent its delivery end. The suction tube 10 has an axial passage 21 which is upwardly and inwardly tapered so that its bottom end may receive within it the centering ring 14 thereby to detachably mount the suction tube 10 in the body 6. The suction tube 10 may have an inlet port 22 adjacent its lower end to effect communication between the well 16 and its axial passage 21.

In the embodiment of our invention shown in Figs. 1 and 2, we have shown the upper end of the suction tube 10 as beveled with its lower edge disposed towards the outlet port 19 and its upper edge having a vertical slot 23. The bottom of the slot 23 intersects the axial passage 21 of the suction tube 10 and its rear part is enlarged as at 24 to establish a seat for the delivery end of the air delivery tube 9 so that the tubes 9 and 10 may be detachably interlocked to prevent the suction tube 10 from becoming accidentally unseated from the centering ring 14 and to maintain the parts of the thus established atomizing unit in operative relation to each other.

By this construction, the atomizing unit may be removed from the body 6 when one of our nebulizers is to be cleansed. By unseating the air delivery tube 9 and withdrawing it, the upper end of the suction tube may be manually engaged and lifted through the open end of the body 6.

To facilitate such manual removal, we may form the suction tube as suggested in Fig. 3. The suction tube 25 of Fig. 3 is substantially longer than the suction tube 10 so that its upper end is nearer the rim 8 of the body 6 thereby to be more conveniently accessible. The suction tube 25 has a flared port 26 disposed towards the outlet port 19 and in communication with the seat 27 for the delivery end of the air tube 9.

While the atomizing units may be otherwise formed, we prefer the construction shown in the drawings as it has the advantage of simplicity of manufacture and ease of assembly and disassembly.

The open end of the body 6 is shown as closed by the cap 7 which has an annular groove to tightly receive the body rim 8 while permitting the cap 7 to be turned. The rim receiving recess is defined by the annular flanges 28 and 29 which snugly engage the outer and inner surfaces, respectively, of the head portion 15 adjacent the rim 8. The flange 29 terminates just above the air delivery tube 9 and includes a skirt

30 having different sized apertures 31 and 32, registerable with the outlet port 19 as the cap is turned. The skirt 30 may conveniently be of sufficient arcuate length so that when the cap 7 is turned to bring its edge 33 into contact with the delivery tube 9, the outlet port 19 is blocked and the nebulizer is effectively sealed. When the cap 7 is turned in the other direction to bring its edge 34 into contact with the delivery tube 9, the smaller aperture 32 registers with the outlet port 19. When the cap 7 is turned into an intermediate position, the larger port 31 registers with the outlet port 19 so that the volume of atomized liquid delivered may be varied.

From the foregoing, it will be apparent that nebulizers in accordance with our invention may be economically manufactured and combine attractive appearance with adaptability for many uses. While our nebulizers may be made from any material, we prefer that they be molded as their parts, when made of a suitable plastic, are interchangeable and well adapted to withstand hard usage.

What we therefore claim and desire to secure by Letters Patent is:

1. A nebulizer comprising a hollow, open-ended body with its closed end constituting a well provided with a centrally located projecting seat and having a pair of ports, air delivering means including an air delivery tube frictionally fitting one of said ports with its extremity in said body and disposed towards the other of said ports, and a tube in said body having a suction passage tapering from its bottom end and at said bottom end being dimensioned to receive said seat and including a portion extending beyond the upper end of said passage to be accessible for digital engagement through the open end of said body, said portion having a passageway into which said air delivery tube extremity is frictionally fitted thereby to lock said suction tube to said body with its lower end anchored in said well and with its upper end and said extremity operatively associated with each other, said suction tube being removable through the open end of said body when said air delivery tube is unseated from said portion.

2. A nebulizer comprising a hollow, open-ended body with its closed end downwardly and inwardly inclined and having a pair of ports, air delivering means including an air delivery tube frictionally fitting one of said ports with its extremity in said body and disposed towards the other of said ports, a tube in said body having a suction passage and including a portion extending beyond the upper end of said passage to be accessible for digital engagement through the open end of said body, said portion having a passageway into which said air delivery tube extremity is frictionally fitted thereby to lock said suction tube to said body with the lower end of its passage in said well and with its upper end and said extremity operatively associated with each other, and means centrally of the bottom of said well engageable with said suction tube to support it, said downwardly and inwardly inclined bottom being available to guide the lower tube end into engagement with said means said suction tube being removable through the open end of said body when said air delivery tube is unseated from said portion.

GEORGE P. TRUMBOUR.
FORBES MACGREGOR.
